M. S. LOONEY

SWING

Filed Nov. 29, 1921

Paul M. Hunt,
T. L. Rosedale

WITNESS:

M. S. Looney
INVENTOR
BY Victor J. Evans
ATTORNEY

UNITED STATES PATENT OFFICE.

MARCUS S. LOONEY, OF AMARILLO, TEXAS.

SWING.

Application filed November 29, 1921. Serial No. 518,597.

To all whom it may concern:

Be it known that I, MARCUS S. LOONEY, a citizen of the United States, residing at Amarillo, in the county of Potter and State 5 of Texas, have invented new and useful Improvements in Swings, of which the following is a specification.

This invention relates to improvements in toys especially designed for the amusement 10 of children and has for an object the provision of a swing, constructed to simulate an airplane.

Another object of the invention is the provision of a swing of the character above 15 set forth, which is suspended by means of supporting cables connected at the front, rear and each side of the swing seat and arranged in such manner that the weight of the occupant will be evenly distributed to 20 the base or main support of the swing.

With the above and other objects in view, the invention further includes the following novel features and details of construction, to be hereinafter more fully described, illustrated in the accompanying drawings and pointed out in the appended claim.

In the drawings, the figure shown is a perspective view of the invention.

Referring in detail to the drawings, 30 wherein like characters of reference denote corresponding parts, the reference character 10 indicates a horizontally arranged longitudinally extending member which forms the base of the swing. Extending transversely of the member 10 substantially centrally of the ends of the latter, is a cross bar 11, the latter being preferably disposed beneath the member 10. Secured upon this last mentioned member and disposed above 35 the cross bar 11 is a seat 12, which includes outwardly divergent side arms 13 which incline toward one another at their rear ends and a back 14, which is secured between the side arms.

40 Mounted upon the forward end of the member 10 are upper and lower wings 15 and 16, which are connected together by struts 17. In addition, these wings are connected by a standard 18, whose lower end is 45 secured to the member 10 by passing through the lower wing 16 and whose upper

end is secured to the upper wing 15. Extending forwardly and centrally from the standard 18 is a shaft 19, upon which is mounted a propeller 20, the latter being capable of rotation.

Extending transversely of the member 10 at the rear of the seat 12 is a second transverse member 21, which is designed to simulate a rudder, while an additional vertically disposed rudder 22 extends rearwardly and upwardly above the rudder 21.

In order to support the swing, there is provided a plurality of cables 23, which are connected at the front to the wing 15, rear 65 to the member 10 and upon each side of the seat 12 to the cross bar 11, through the medium of suitable eyes or other fastening devices as indicated at 24. The eye which serves as a connection for the front cable 70 23 is secured through the upper wing 15 into the standard 18 so as to provide a proper connection between the swing and cable. The opposite ends of the cables are connected with a hook 25, by means of 75 which the swing may be secured to a suitable support.

The invention is susceptible of various changes in its form, proportions and minor details of construction and the right is 80 herein reserved to make such changes as properly fall within the scope of the appended claim.

Having described the invention what is 85 claimed is:—

A toy airplane of the character described comprising a horizontally arranged longitudinally extending member, a cross bar secured to the longitudinal member substantially central of the underside thereof, a 90 seat secured upon the longitudinal member above the cross bar and including converging side pieces and a back, superimposed wings supported upon the longitudinally extending member in advance of the seat, 95 a standard connecting the wings, a propeller associated with said standard, a horizontally arranged transversely disposed member secured to said longitudinally extending member at the rear of the seat, a vertically 100 arranged longitudinally disposed member extending rearwardly and upwardly from

the transverse member, a pair of supporting cables, fastening means secured to the upper wing and adjacent the rear end of the longitudinally extending member respectively for receiving the ends of one cable, fastening means secured adjacent the ends of the cross bar and receiving the ends

of the other cable, and a support for receiving the cables as and for the purpose specified.

In testimony whereof I affix my signature.

MARCUS S. LOONEY.
